UNITED STATES PATENT OFFICE.

MAX A. BERGWARDT, OF ELIZABETH, NEW JERSEY.

PICOT-EDGING ATTACHMENT.

1,264,886.

Specification of Letters Patent.

Patented May 7, 1918.

Application filed July 29, 1916. Serial No. 112,100.

To all whom it may concern:

Be it known that I, MAX A. BERGWARDT, a citizen of the United States, and a resident of Elizabeth, in the county of Union 5 and State of New Jersey, have invented a certain new and useful Improvement in Picot-Edging Attachments, of which the following is a full, clear, and exact specification.

10 This invention relates to a class of devices adapted to be employed in conjunction with hemstitching machines.

My invention has for its object primarily to provide a device, or attachment designed 15 to be applied to a hemstitching machine whereby a form of trimming for women's garments commonly known as picot edging may be produced without requiring any handwork as is incident to methods ordinarily in use, and which is of a form so 20 that the requirement for detaching the device from the machine when not employed may be obviated. The invention consists essentially of a cutter preferably in the form 25 of a pair of scissors which is adapted to be applied to a hemstitching machine so as to be operated for separating the connected stitches of the hemstitching when the machine is operated, and connecting the cutter 30 with the piercer bar of the machine is a form of mechanism whereby the cutter will be operated simultaneously with the operation of the piercer for making hemstitch holes.

35 Other objects of the invention are to provide for the cutter a supporting bracket adapted to be adjustably attached to the presser-foot bar of the machine; to provide means whereby the cutter may be adjusted 40 relatively to the presser-foot of the machine; and to provide a picot edging attachment of a simple, efficient and durable construction.

45 With these and other objects in view the invention will be hereinafter more particularly described with reference to the accompanying drawings forming a part of this specification in which similar characters of reference indicate corresponding parts in all 50 the views, and will then be pointed out in the claims at the end of the description.

In the drawings, Figure 1 is a fragmentary view showing a side elevation of one 55 form of picot edging attachment embodying my invention as applied to a hemstitching

machine, the needles and piercers of the machine being in lowered positions.

Fig. 2 is a fragmentary view showing an opposite side elevation of the device and the parts of the machine shown in Fig. 1. 60

Fig. 3 is a fragmentary view showing a side elevation of the device with the needles and piercers of the device in elevated positions.

Fig. 4 is a fragmentary view showing a 65 front elevation of the presser-foot and its bar together with the piercer of the machine with the device attached thereto.

Fig. 5 is a fragmentary view showing a 70 rear elevation of the device attached to the presser-foot bar and to the piercer of the machine.

Fig. 6 is a sectional view, partly in detail, taken on the line VI—VI of Fig. 3.

Fig. 7 is a front elevation of the piercer 75 and supporting bracket of the machine.

Fig. 8 is a side elevation thereof.

Fig. 9 is a side view of one of the links 80 of the mechanism for operating the cutter.

Fig. 10 is an edge view thereof.

Fig. 11 is a side view of the second link of 85 the mechanism for operating the cutter.

Fig. 12 is a section taken on the line XII—XII of Fig. 11.

Fig. 13 is a side elevation of the supporting bracket of the cutter of the device. 90

Fig. 14 is a rear elevation of the supporting bracket.

Fig. 15 is a top plan of the supporting bracket. 95

Fig. 16 is an inverted plan thereof.

Fig. 17 is a sectional view, partly in detail, taken on the line XVII—XVII of Fig. 15, and

Fig. 18 is a sectional view, partly in detail, taken on the line XVIII—XVIII of 100 Fig. 1.

The device, or edging attachment has a supporting bracket 10 formed of a substantially square plate 11 with an opening 12 in its central part adjacent to one of its edges to allow the plate to be removably guided over the lower end part of the spring actuated presser-foot bar, as 13, adapted to be 105 yieldingly moved upwardly and downwardly in the head 13^a of a hemstitching machine which may be of a well-known make, and on the lower end of the bar 13 is a presser-foot 14 of the usual type having two spaced prongs, or toes 15 and 16. The ma- 110

chine is also provided with a reciprocable bar 17 carrying two spaced needles 18 and 19 to which a vibratory movement is imparted by levers, as 20 and 21, which are operated in unison with the needle bar 17, and between this needle bar and the presser-foot bar 13 is a reciprocable bar 22 on which is held a bracket 23 having on its lower end a well-known form of piercers, as 24, for making the usual holes in the material being hemstitched, while in front of the needles 18 and 19 is the customary auxiliary piercer, as 25, held to the needle bar 17 by a bracket, as 26, the needle bar 17 and piercer bar 22 being operable with the operation of the machine to simultaneously operate the needles 18 and 19, piercer 24 and auxiliary piercer 25.

The supporting bracket 10 of the device is arranged on the presser-foot bar 13 of the machine so that the plate 11 extends transversely in a rearward direction relatively to this bar as well as rearwardly with respect to the presser-foot 14, and to hold the bracket to the bar 13 against accidental movement, through the plate 11 is a threaded opening in which is a set-screw 26 engaging the presser-foot bar. Projecting upwardly from the plate 11 so as to be spaced from the presser-foot bar 13 is an arm 27 having a bifurcated upper end to provide a vertically disposed slot, as 28, and in the bifurcated parts of this arm are registered threaded openings through which a screw 29 is passed, while in the upper free end of the arm 27 is another threaded opening in which is a set-screw 30 adapted to be rotated into engagement with the screw 29 for locking this screw 29 against movement. Extending angularly in a lateral direction from the upper part of the arm 27 of the bracket 10 is a finger 31 with a hole 32 therethrough, and projecting downwardly from the underside of the plate 11 of the supporting bracket is an extension 34 of the shape of substantially an inverted U to provide a vertically disposed circular slot 35 between the arms of the extension, and through the plate 11 of the bracket 10 is a diagonally disposed threaded passage 36 communicating with the upper end of the slot. The U-shaped extension 34 is arranged so that its slot 35 is in register with the space between the toes 15 and 16 of the presser-foot 14 of the machine, and from the lower ends of the arms of the U-shaped extension are two spaced fingers 37 and 38 angularly disposed toward the rear end of the presser-foot so as to be slightly spaced thereabove.

To produce picot edging the material is first hemstitched by operating the machine for working the needles 18 and 19 with the piercers 24 and 25 in the usual manner and heretofore it has been the custom to separate by handwork the stitches connecting the

hemstitching. In order to sever these connecting stitches by the use of my device simultaneously with the accomplishment of the hemstitching, an adjustable cutter, as 39, is provided. The cutter 39 is preferably in the form of a pair of scissors having two blades, as 40 and 41, which are adjustably arranged between the fingers 37 and 38 of the slotted extension 34 of the supporting bracket 10, and the central parts 70 of the blades of the scissors are pivoted, at 42, to the finger of the supporting bracket. The cutter, or scissors 39 are arranged so that the blades 40 and 41 will be moved relatively to each other in upwardly and 80 downwardly directions, and the forward parts of the blades are of lengths to extend into the space between the toes of the presser-foot 14 of the machine contiguous to the piercer 24, while the opposed edges 85 of the blades are sharpened to a keen cutting edge, as at 43 and 44. The opposite parts of the blades are of lengths to extend some distance rearwardly of the supporting bracket 10 of the device, and these ends 90 of the blades may be curved upwardly, as at 45 and 46, respectively. In the curved end 45 of the blade 40 of the scissors is a hole in which is held the lower end of a spiral spring 48 having its other end held 95 in the opening 32 of the finger 31 of the slotted arm 27 of the bracket 10, and this spring normally serves to force the cutting end of the blade 40 downwardly between the toes of the presser-foot by forcing the 100 rear end of this blade in an upward direction.

The cutter 39 is operable in unison with the operation of the needles 18, 19 and with the piercers 24 and 25 when the machine 105 is operated, and to accomplish this, a mechanism, as 49, is provided. The mechanism 49 may be in the form of an adjustable connection composed of two extensible members 50 and 51. The member 50 has a link, or 110 bar 52 with its lower end pivoted, at 53, to the curved end 46 of the blade 41 of the cutter, or scissors 39, and this link has a set screw 54 threaded in an opening in its upper end. The screw 54 passes through a 115 slot 55 provided in the lower part of a second link, or bar 56 of the member 50 to allow the links to be extensibly adjusted for lengthening or shortening this member. The member 51 has a bar 57 with one of 120 its ends pivoted, at 58, to the upper end of the bar 56 of the member 50, and in the central part of the bar 57 is a slot 59. The bar 57 of the member 51 is movably disposed in the slot 28 of the arm 27 of the supporting bracket 10, and through the slot 59 of this bar is passed the screw 29 of the arm 27 of the bracket. The bar 57 of the member 51 is thereby adapted to be rocked in the slot 28 of the arm 27 of the 130

supporting bracket, and extending outwardly from one of the faces of this bar at its second end are two spaced flanges, or lugs 60 and 61. To the lugs 60 and 61 is pivoted, at 62, one end of an arm 63 adapted to be swung laterally toward and from the bar 57 of the member 51, and on the free end of the arm 63 of the bar 57 is a ring 64. The ring 64 is adapted to be removably guided over a screw 65 extending from the upper part of the bracket 23 of the piercer 24 for fastening the member 51 to this bracket, and to prevent the ring from accidental displacement on the screw 65 to the bracket 23 of the piercer 24 is pivoted, at 66, an upwardly swinging bar 67 adapted to be moved in frictional engagement with the exposed face of the screw 65 after the ring 64 of the member 51 is arranged thereon.

To adjust the cutter, or scissors 39 relatively to the presser-foot 14 of the machine for properly separating the connecting stitches of the hemstitching in the slot 35 of the extension 34 of the supporting bracket 10 is a movable block 68, Figs. 14, 16, 17, and in the threaded opening 36 of the plate 11 of the supporting bracket is a finger screw, as 69, adapted to be rotatably moved into contact with the upper end of the block so as to be forced downwardly in the slot 35 against the upper edge of the rear part of the blade 41 of the cutter, or scissors against the tension of the spring 48. This blade of the scissors may thereby be accurately positioned in the path of the connecting stitches of the hemstitching while the material is being hemstitched for separating the connecting stitches, and by accordingly adjusting the extensible links 50 and 51 of the mechanism 49 the blade 40 of the scissors may be suitably adjusted with relation to the blade 40 for causing the scissors to properly operate.

When the machine is operated to produce hemstitching of material in the usual manner, and when the piercer bracket 23 is reciprocated by the reciprocation of the bar 22 of the piercer 24, the link 51 of the mechanism 49 will be rocked to impart upward and downward movements to the blade 41 of the cutter, or scissors, and as the blade 40 is yieldingly movable the scissors will then operate in unison with the operation of the machine to cut the connecting stitches of the hemstitching to produce with facility picot edging. To dispense with the use of the device, for instance when it is desired to employ the machine to accomplish hemstitching alone without detaching the device, the screw 26 of the supporting bracket 10 is loosened from its engagement with the presser-foot bar 13, and the device is rotatably swung so that the cutting ends of the 65 scissors will rest on one of the toes of the

presser-foot, 14, as shown at 70 Fig. 6, following the raising of the finger-screw 69 to free the pressure of the block 68 on the blade 41 of the scissors.

In the foregoing description, I have embodied the preferred form of my invention, but I do not wish to be understood as limiting myself thereto, as I am aware that modifications may be made therein without departing from the principle, or sacrificing any of the advantages of this invention, therefore I reserve to myself the right to make such changes as fairly fall within the scope thereof.

Having thus described my invention, I claim as new and desire to secure by Letters Patent:—

1. In a picot edging attachment, the combination with a supporting bracket operatively carrying a pair of scissors, adapted to be applied to the presser-foot bar of a hemstitching machine having a reciprocable piercer-bar, of a member formed of extensibly adjustable links one being pivoted to one of the blades of scissors, a rocking bar 90 on the bracket, having one of its ends pivoted to the second link of said member and having its other end pivoted to the piercer-bar, and means connecting the second blade of the scissors to the bracket for normally retaining in depressed position the cutting end of said second blade between the toes of the presser-foot of the machine.

2. In a picot edging attachment, the combination with a supporting bracket operatively carrying a pair of scissors, adapted to be removably applied to the presser-foot bar of a hemstitching machine having a reciprocable piercer-bar, of a member formed of extensibly adjustable links one being pivoted to one of the blades of the scissors, a rocking bar on the bracket, having one of its ends pivoted to the second link of said member and having its other end pivoted to the piercer-bar, means connecting the second blade of the scissors to the bracket for normally retaining in depressed position the cutting end of said second blade between the toes of the presser-foot of the machine, and means on the bracket, operable for allowing the cutting ends of the scissors to be adjustably raised and lowered between the toes of said presser-foot.

3. In a picot edging attachment, the combination with a supporting bracket operatively carrying a pair of scissors, adapted to be removably applied to the presser-foot bar of a hemstitching machine having a reciprocable piercer-bar, of an extensibly adjustable member having one of its ends pivoted to one of the blades of the scissors, a rocking bar on the bracket, having one of its ends pivoted to the second end of said member, means hinged to the second end of the rocking bar as well as being pivoted to the

4
pierce-bar whereby said blade of the scissors will be swung upwardly and downwardly with the reciprocation of the piercer-bar, and means connecting the second blade of the scissors to the bracket for normally retaining in depressed position the cutting end of said second blade between the toes of the presser-foot of the machine.

5. In a picot edging attachment, the combination with a supporting bracket operatively carrying a pair of scissors, adapted to be removably applied to the presser-foot bar of a hemstitching machine having a reciprocable piercer-bar, of an extensibly adjustable member having one of its ends pivoted to one of the blades of the scissors, means on the bracket as well as being connected to the extensible member and connected to the piercer-bar whereby the

piercer-bar when reciprocated will impart 20 reciprocation to said member to cause the blade of the scissors to move upwardly and downwardly, means connecting the second blade of the scissors to the bracket for normally retaining in depressed position the 25 cutting-end of said second blade between the toes of the presser-foot of the machine, and means on the bracket, operable for allowing the cutting ends of the scissors to be adjustably raised and lowered between the toes of 30 said presser-foot.

This specification signed and witnessed this 28th day of July, A. D. 1916.

MAX A. BERGWARDT.
